UNITED STATES PATENT OFFICE.

EDWARD WEISSENBORN, OF HOBOKEN, NEW JERSEY.

LEAD-PENCIL HOLDER.

SPECIFICATION forming part of Letters Patent No. 250,023, dated November 22, 1881.

Application filed September 9, 1881. (No model.)

To all whom it may concern:

Be it known that I, EDWARD WEISSENBORN, of Hoboken, in the county of Hudson and State of New Jersey, have invented a new and useful

5 Improvement in Lead-Pencil Holders, of which the following is a full, clear, and exact description, reference being had to the accompanying drawings, forming part of this specification, in which similar letters of reference indicate corresponding parts in all the figures.

10 Figure 1 is a longitudinal section of my improvement. Fig. 2 is a side elevation of the lower part of the same. Fig. 3 is a plan view of the blank for the pencil-holder point. Fig. 15 4 shows a modification of the blank for the pencil-holding point. Fig. 5 is a side elevation of the modified pencil-holding point. Fig. 6 is a cross-section of the same, taken through the line $x x$, Fig. 5.

20 The object of this invention is to facilitate and cheapen the manufacture of lead-pencil holders of that class in which the lead is held by a spring-pressed divided point.

The invention consists in a novel construction and arrangement of parts, as hereinafter 25 fully described, and pointed out in the claims.

A represents a tube of such a length and size as to receive and fit loosely upon a lead-pencil, B.

30 To the tube A, a little above its center, is attached a collar, C, which is secured to the ring-collar D, secured within and to the lower end of a tube, E. The tube E surrounds the upper part of the tube A, and has a rubber eraser, F, attached to its upper end, which serves also as a knob for the finger to rest upon when pressing down the tubes A E. If desired, the eraser F can be omitted and replaced with a knob.

40 To the tube A, at a little distance from its lower end, is attached a collar, G, which rests against the collar H, secured to the upper end of a short tube, I, by serrating the said upper end of the said tube I, and bending the points 45 thus formed down over the said collar H. The enlargement formed by serrating the upper end of the short tube I rests upon a shoulder or in a bead, J, formed in the outer tube or case, K, of the holder, and keeps the said tube I in place in the said case K. The case or tube K

extends nearly to the upper end of the tube E, as shown in Fig. 1. Around the upper part of the tube K is formed a bead or shoulder, L, for the fingers of the operator to rest against when pushing down the tube E.

55 The tube A, when left free, is held up by a spiral spring, M, placed upon the middle part of the said tube A, with its upper end resting against the collar C, and its lower end resting against the collar H. The spring M is covered and protected by the tube or case K.

60 The pencil B is held by the spring-point N, which is formed of a strip of elastic sheet metal having its lower part cut to form tapering fingers or jaws O. The plate or strip is 65 then bent in its upper part into tubular form, and in its lower part into conical form, as shown in Figs. 1 and 2, so that the ends or points of the jaws O will grasp and hold the pencil B. The spring-point N fits into the short tube 70 I, and has its upper edge slightly bent outward to rest upon the upper end of the tube I at the base of its points.

75 With this construction, when the tube E is pressed downward, it carries the tube A with it and compresses the spring M, so that the said spring M will raise the said tube A to its place as soon as the tube E is released. When the tube A is forced downward its lower end strikes against the inclined inner surfaces of the spring-point N, and forces the parts or jaws of the 80 said spring-point open, allowing the pencil B to drop down freely. When the pencil B has been adjusted in the desired position, the tube E is released, and the spring M forces the tube 85 A upward and allows the parts or jaws O of the divided point to spring inward to clasp and hold the said pencil B.

If desired, the divided spring-point can be made in three pieces, as shown in Fig. 4; but 90 in this case a small tube, P, should be inserted in the tubular upper part, N', of the said divided point to keep its separated parts in place.

If desired, the tube P can be placed within the tubular upper part of the divided point N 95 O, when the said point is made in one piece, as first described.

Having thus described my invention, I claim as new and desire to secure by Letters Patent—

1. In a lead-pencil holder, the combination, 100

with the tube K and the spring-point N O, of the tube I, provided with the shoulder H, the pencil-receiving tube A, provided with shoulders C G, the sliding tube E, and the spring M, substantially as and for the purpose set forth.

2. In a lead-pencil holder, the combination, with the tube K, provided with the bead J, of

the short tube I, having its upper end serrated and provided with the collar H, substantially as and for the purpose set forth.

EDWARD WEISSENBORN.
